UNITED STATES PATENT OFFICE.

HENRY GUY CARLETON, OF NEW YORK, N. Y., ASSIGNOR TO THE CARLETON ELECTRIC COMPANY, OF SAME PLACE.

LOCK.

SPECIFICATION forming part of Letters Patent No. 656,011, dated August 14, 1900.

Application filed November 15, 1899. Serial No. 737,086. (No model.)

To all whom it may concern:

Be it known that I, HENRY GUY CARLETON, a citizen of the United States, residing at New York, county of New York, and State of New York, have invented certain new and useful Improvements in Locks, fully described and represented in the following specification and the accompanying drawings, forming a part of the same.

10 This invention relates to certain improvements in locks.

In one class of electric locks as now ordinarily constructed the movable part which opens the lock—such, for instance, as the sliding bolt—is operated by the magnet, the attractive force of the magnet being either exercised directly on the bolt or utilized to actuate certain mechanical agencies which in turn operate the bolt. In another class of 20 electric locks the magnet is located in the operating connections and serves to tie or secure together certain parts of the train of connections which extend from the operating device to the bolt or other movable part, the power 25 for opening the lock being in this class applied by hand. A lock of this type is shown in my Patent No. 608,321, granted August 2, 1898.

In the first class of locks above referred to 30 magnets of very considerable strength and requiring a considerable amount of battery-power are necessarily employed. In the second class of locks the strength of the magnets and the amount of battery-power is largely 35 reduced; but since the magnet is located in the connections and serves in a way to tie certain parts of the connections together its attractive force is still required to be considerable. Furthermore, the circuit-controlling devices ordinarily employed in electric locks are, as a rule, located outside the casing of the lock and are operated by agencies independent of the lock-operating mechanism. In 40 opening said locks, therefore, it is necessary to first close the circuit, the circuit then remaining closed until the lock is operated. If, as may happen, some little time elapses between the closing of the circuit and the operation of the lock, considerable battery-power 45 is used, and with open-circuit batteries it

sometimes happens that the battery becomes exhausted before the lock is operated.

A further objection to electric locks as now ordinarily constructed is that they are only provided with one set of operating means and can therefore only be operated through the electrical devices. If, therefore, it happens that there is any break in the circuit connections, or if the electrical devices fail to act for any reason, the lock becomes inoperative and cannot be opened until the electrical connections are rendered operative or the lock is either picked or taken to pieces.

It is one of the objects of the present invention to produce an improved lock which shall embody all the advantages of an electric controlling mechanism and in which at the same time the engaging part, which is moved to open the lock, shall be operated entirely by mechanical devices, thereby enabling a large amount of force to be used when necessary to open the lock, and at the same time very little battery-power is required to operate the controlling devices.

A further object of the invention is to construct the circuit-closing devices for electric locks in such a way as to cause them to be operated by the means by which the movable engaging part of the lock is moved, thereby conserving the power of the battery employed, as no battery-power is consumed until the lock is actually operated.

A further object of the invention is to produce an improved lock which shall be provided with a plurality of actuating devices, one of said devices being purely mechanical and the other being electrically controlled.

A further object of the invention is to produce an improved form of electric controlling mechanism for use in connection with electrically-operated locks and other similar devices.

With these and other objects in view the invention consists in certain constructions and in certain parts, improvements, and combinations, as will be hereinafter more fully described and then pointed out in the claims hereunto appended.

In the accompanying drawings, which form a part of this specification, and in which like

characters of reference indicate the same parts, Figure 1 is a vertical sectional view illustrating a portion of a door or other part provided with a lock, the lock being shown 5 in position therein, partly in section and partly in elevation. Fig. 2 is a horizontal section on the line 2 of Fig. 1. Fig. 3 is a diagrammatic view of the circuits employed.

Referring to the drawings, which illustrate 10 a preferred embodiment of the invention, 1 indicates a door or other movable part in which the lock-casing 2 is located. The jamb is indicated at 3, said jamb being provided with the ordinary keeper 4.

15 The bolt mechanism of the lock may be of any usual or desired form. In the present instance it consists of a sliding bolt 5, said bolt working in an opening in the lock-casing 2 and in a supporting guide or loop 7. The 20 bolt is held forward to its duty by the usual spring 8.

25 When the bolt is the moving part by which the lock is opened, as in the lock shown, it will be provided with suitable means which are engaged by the operating connections when it is to be slid. While these means may be of any suitable form, in the present instance the bolt is provided with a projection or shoulder 9, said shoulder preferably extending from both sides thereof and being 30 preferably cast in one piece with the bolt.

35 The lock shown is provided with two sets of devices, one of these devices being a purely-mechanical operating device and the other being electrically controlled. The electrically-controlled operating device may be widely varied in form. In the present instance it consists of a movable member which is in the form of an open or frame-shaped 40 slide 10, the sides of which are connected at their outer ends by a cross-piece 11. One of the sides of the slide is preferably provided with an extension 12, on which is formed a rack 13, this rack being engaged by an actuating device to be hereinafter described. 45 While the movable member which operates the engaging part is shown as a slide, it is to be understood that it may be differently constructed, if desired, and that it may be operated by means other than the rack referred to.

50 The slide is supported in the lock-casing in any suitable manner. It is shown as supported by a bracket 14 and by a projection 15, the slide itself passing through an opening in the bracket 14 and the rack extension 12 moving in a groove in the projection 15.

55 The actuating device by which the slide is moved may be widely varied in construction. In the lock shown the ordinary knob-spindle 60 16, which carries the knob 17, is provided with a toothed segment 18 and with the usual torsion returning-spring 19. The segment 18 is so arranged as to permit a limited movement of the spindle before its teeth come into engagement with the rack-teeth 13. The purpose of this limited or lost movement will be hereinafter explained.

The slide 10 may be returned after operation by the segment in any suitable or desired manner. In the lock shown a spring 20 connects with the cross-piece 11 and with a suitable eye 21, secured in the lock-casing. 70

A controller which is preferably electrically operated is provided, the purpose of this device being to so control the operation of 75 the parts of the lock as to make the movement of the withdrawing mechanism effective to operate the movable engaging part of the lock, which in the construction shown is the bolt. This controlling device may be widely 80 varied in location, construction, and operation, and the term "controller" as used in the specification and claims is to be understood as covering any device by which the movement of the slide or other withdrawing 85 mechanism is made effective to withdraw the other engaging part of the lock. In the lock shown the controller operates upon the slide and regulates the amount of its movement; but constructions in which the controller does 90 not operate upon the slide are possible and within the invention. In the present construction the controller consists of a part 22, which is arranged to move with the slide preferably by being pivoted thereto, the pivot 95 for said controller being at the point 23. The said controller in the form shown is provided with a hooked end 24 and a cam-face 25. The hooked end of the controller engages under certain circumstances with a stop 26, 100 said stop being in the lock illustrated located behind the bracket 14, and under other circumstances moves over the stop without engaging it.

The position of the controller is determined 105 by means of a suitably-arranged electromagnet, the coils 27 of which are mounted on a suitable base 28, the base being secured in any suitable manner to the lock-casing 2. The pole-pieces 29 of the magnet are arranged 110 so as to be just over the path of travel of the pivoted controller 22, and the controller thus forms the armature for said pole-pieces.

From the construction so far described it will be obvious that when the shaft 16 is operated by the knob 17 and the segment 18 engages the rack-teeth 13 the slide 10 will be drawn back. If now a circuit be established 115 through the magnet, the controller 22 will be held up in the position shown in Fig. 1. The slide 10 can therefore be drawn back, so that its connecting-piece 11 strikes the projection 9 on the bolt and causes the bolt to move back with the slide. If, however, a circuit is not established through the magnet, as soon 120 as the slide moves far enough so as to draw the hooked end 24 of the controller off the bracket 14 the controller will drop by gravity, and its hooked end will engage the stop 26. The stop 26 is so located as to be engaged by the controller before the cross-bar 11 reaches the position where it engages the projection 9. As soon therefore as the hooked end 24 of the controller 22 engages

the stop 26 the further movement of the slide is checked and the bolt cannot be drawn back.

While the armature-controller 22 may, if desired, be allowed to come in contact with the pole-pieces of the magnet, the construction will preferably be arranged so as to prevent any actual contact between the armature-controller and the pole-pieces, thereby reducing the friction and the amount of power necessary to draw back the slide. In order to effect this function, the construction will preferably embody a stop-arm 30, carrying a friction-roller 31, which is so located as to just prevent the armature when the magnet is energized from coming against the pole-pieces.

While the circuit-controlling devices for the magnet-circuit may be located in any suitable place and operated in any suitable manner, they are preferably arranged inside the lock and are operated by the actuating mechanism of the lock. To this end a spring 32 is provided, said spring forming one terminal of the magnet-circuit. In the construction shown this spring is mounted on a suitable insulating-block 33. It may, however, be arranged and mounted in any suitable or desired manner. The spring 32 lies in the path of a circuit-closing projection 34, said projection being preferably carried by the knob-shaft 16 and being segmental in form.

It will of course be understood that when a set of circuit-controlling devices such as have been described is located inside the lock the circuit will be provided with a second set of controlling devices located at another point. This second set of circuit-controlling devices may be of any suitable form and may be located in the building or apartment in which the lock is located, or, if desired, they may be in the door itself. In case they are located in the door itself these circuit-controlling devices will preferably be of the construction shown in my pending application, Serial No. 731,391, filed September 23, 1899. A full description of these circuit-controlling devices is unnecessary for the purpose of this application. It may be said, however, that in general they consist of a key-operated barrel, which is indicated at 35, said barrel carrying a circuit-closing projection 36, which co-operates with a terminal 37. When the barrel is turned by the key, the projection 36 will contact with the terminal 37 and the circuit will be closed. The closing of the circuit at this point having been effected either by the devices which have just been described or by any other suitable devices, such as a switch or button, when the shaft 16 is turned by means of the knob 17, the segmental circuit-closing projection 34 strikes the terminal spring 32. This closes the circuit through the magnet. The further rotation of the shaft 16 brings the segment 18 into engagement with the rack 13 and draws back the slide 10, the magnet operating to hold the controller 22 in inoperative position, as has been before described.

By this arrangement of circuit-controlling devices no battery-power is consumed until the lock is actually operated.

As has been before stated, a second set of devices is provided for operating the lock. While this set of devices may be widely varied in construction, in the lock shown they consist of a slide 38, which is supported in the lock-casing in any suitable manner, as by guides 39, and is provided with an upturned projection 38'. The slide 38 is provided with rack-teeth 40, which are engaged by a segment 41, carried on a spindle 42, the said spindle being provided with a knob 43. This knob 43 will be preferably located inside the room or building in which the lock is placed. The occupant of the room or building will by means of this device be able to operate the lock entirely independent of the electric-controlled device hereinbefore described.

Any suitable arrangement of circuits may be employed for energizing the magnet. A suitable set of circuits is indicated in Fig. 3, in which the battery is marked 44. From this battery a wire 45 is led to the spring-terminal 37. Another wire 46 is led from the revolving barrel 35, before referred to, to the segmental circuit-closing projection 34. From the spring 32 a wire 47 is led to the magnet-coils 27, and from these coils a wire 48 leads to the battery. The operation of this circuit is apparent, and a detailed description thereof is unnecessary.

It will be understood that the details of construction by which this invention is carried into effect may be varied within wide limits, and it is obvious that some features of the invention are capable of use independently of other features and in locks which are not electrically controlled. It is to be understood, therefore, that such independent use of these features is contemplated. The invention is not therefore to be limited to the specific construction which is herein described.

What I claim is—

1. In a lock, the combination with one of the engaging parts, of a withdrawing mechanism including an actuating device and suitable mechanical connections between said device and the part, a normally-inoperative controller for the withdrawing mechanism, and suitable electrical devices for causing the controller to remain inoperative, substantially as described.

2. In a lock, the combination with one of the engaging parts, of a withdrawing mechanism including an actuating device and mechanical connections between said device and the engaging part, said connections being constructed to permit a limited movement of the withdrawing mechanism without moving the engaging part, a controller for the withdrawing mechanism, and suitable electrical devices for actuating the controller, substantially as described.

3. In a lock, the combination with one of the engaging parts, of a withdrawing mechanism including an actuating device and suitable movable mechanical connections between said device and the engaging part, a controller mounted on said connections, and a suitably-located magnet for actuating the controller, substantially as described.
4. In a lock, the combination with one of the engaging parts, of a withdrawing mechanism including an actuating device, of suitable mechanical connections between said device and the engaging part, a normally-inoperative controller mounted on said connections, and a suitably-located magnet for causing the controller to remain inoperative, substantially as described.
5. In a lock, the combination with one of the engaging parts, of a movable member for operating said part, a controller, a connection between the controller and the member whereby it moves with the member, and means whereby the controller is actuated so as to make the movement of the member effective to move the engaging part, substantially as described.
6. In a lock, the combination with one of the engaging parts, of a movable member for operating said part, a controller, a connection between the controller and the member whereby it moves with the member, and electrically-operated means whereby the controller is actuated so as to make the movement of the member effective to move the engaging part, substantially as described.
7. In a lock, the combination with one of the engaging parts, of a movable member for operating the part, a moving controller by which the movement of the movable member is made effective to operate the engaging part, and a suitably-located magnet across the field of which the controller moves and by which it is actuated, substantially as described.
8. In a lock, the combination with one of the engaging parts, of a withdrawing mechanism including an actuating device, and a movable member adapted to engage said part, a normally-inoperative controller, and electrically-operated means for causing the controller to remain inoperative, substantially as described.
9. In a lock, the combination with one of the engaging parts, of a slide by which said part is operated, means for moving the slide, a normally-inoperative controller for the slide, and electrically-operated means for causing the controller to remain inoperative, substantially as described.
10. In a lock, the combination with one of the engaging parts, of a movable member, means for actuating the member, a controller for the member mounted thereon, and a suitably-located magnet for determining the position of the controller, substantially as described.
11. In a lock, the combination with one of the engaging parts, said part having a projection, of a movable operating member therefor also provided with a projection, means for actuating the member, a normally-inoperative pivoted controller carried by the member, a stop with which the controller engages, the parts being constructed to permit the member to have a limited movement before the controller comes into operation, and means for causing the controller to remain inoperative, substantially as described.
12. In a lock, the combination with one of the engaging parts, said part having a projection, of an operating member therefor also provided with a projection, means for actuating the member, a pivoted controller carried by the member, a stop with which the controller engages, the parts being constructed to permit the member to have a limited movement before the controller comes into operation, and means for rendering the controller inoperative, substantially as described.
13. In a lock, the combination with one of the engaging parts, said part having a projection, of a movable operating member therefor also provided with a projection, means for actuating the member, a pivoted controller carried by the member, a stop with which the controller engages, the parts being constructed to permit the member to have a limited movement before the controller comes into operation, and electrically-operated means for rendering the controller inoperative, substantially as described.
14. In a lock, the combination with one of the engaging parts, said part having a projection, of an operating-slide therefor also provided with a projection, means for actuating the slide, a pivoted controller carried by the slide, a stop with which the controller engages, the parts being constructed to permit the slide to have a limited movement before the controller comes into operation, and electrically-operated means for rendering the controller inoperative, substantially as described.
15. In a lock, the combination with one of the engaging parts, of a movable member, a controller, a connection between the controller and the member whereby it moves with the member, means for operating the controller so as to make the movement of the movable member effective to open the lock, and means for actuating the member, substantially as described.
16. In a lock, the combination with one of the engaging parts, of a movable member for operating said part, a controller, a connection between the controller and the member whereby it moves with the member, means for operating the controller so as to permit the movable member to open the lock, and means for actuating the member, substantially as described.
17. In a lock, the combination with one of the engaging parts, of a slide independent of said part, a controller moving with the slide, means for actuating the controller, and means

for actuating the slide, substantially as described.

18. In a lock, the combination with one of the engaging parts, of a slide, means whereby the slide is caused to move the said engaging part to open the lock, a controller moving with the slide, means for rendering the controller inoperative when the lock is to be opened, and means for actuating the slide, substantially as described.

19. In a lock the combination with one of the engaging parts of a hand-actuated device, moving means between the hand-actuated device and the engaging part whereby said part may be operated, a controller, a connection between said controller and the means whereby the controller moves with the means and suitable electrical devices for operating the controller, substantially as described.

20. In a lock, the combination with one of the engaging parts, of a slide independent of said part, a hand-actuated device for operating the slide, a controller moving with the slide, and a magnet located along the path of movement of the controller and operating to determine the position of the controller, substantially as described.

21. In a lock, the combination with one of the engaging parts, of a member for operating said engaging part, means for actuating said member, a controller moving with the member, a magnet located alongside the path of movement of the controller, the controller forming the armature for the magnet, and means for preventing the controller from touching the poles of the magnet, substantially as described.

22. In a lock, the combination with a movable member, of means for actuating the member, a controller moving with the member, and a magnet for determining the position of the controller and thus making the movement of the member effective to open the lock, substantially as described.

23. In a lock the combination with a movable member of means for actuating the member, a controller, a connection between the controller and the member whereby the controller moves with the member, a suitably-located magnet for which the controller forms the armature and across the field of which it moves, and means whereby the movable member is caused to open the lock, substantially as described.

24. In a lock, the combination with a slide of means for actuating the slide, a controller, a connection between the controller and the slide whereby the controller moves with the slide, a magnet for which the controller forms the armature and across the field of which it moves, and means whereby the slide is caused to open the lock, substantially as described.

25. In a lock, the combination with a movable member, of a pivoted controller therefor moving with the member, means for holding the controller in a normally-inoperative position, a magnet, and means for energizing it,

said magnet being located so as to act upon the controller and retain it in its normally-inoperative position when the magnet is energized, and means engaged by the controller when the magnet is deenergized, whereby the controller determines the movement of the member, substantially as described.

26. In a lock, the combination with one of the engaging parts, said part being provided with a projection, of a slide, means controlled by the slide for engaging the projection, guides for the slide, a controller moving with the slide, said controller being normally held in inoperative position, a magnet and means for energizing it, said magnet being arranged to operate upon the controller, and a stop located in the path of the controller and engaged thereby when the magnet is deenergized, and means for moving the slide and controller, substantially as described.

27. In a lock, the combination with a bolt having a projection, of a slide having a projection which engages the projection on the bolt, a controller pivoted on the slide, a magnet located in the path of the controller, and operating when energized to hold the controller in an inoperative position, a stop engaged by the controller when the magnet is deenergized, a rack for operating the controller, and a hand-operated segment for operating the rack, substantially as described.

28. In a lock, the combination with a bolt having a projection, of a slide having a projection which engages the projection on the bolt, a controller pivoted on the slide, a magnet located in the path of the controller and operating when energized to hold the controller in an inoperative position, the controller forming the armature for the magnet, means for preventing the controller from touching the poles of the magnet, a stop engaged by the controller when the magnet is deenergized, a rack for operating the controller, and a hand-operated segment for operating the rack, substantially as described.

29. In a lock, the combination with one of the engaging parts, said part having a projection, of a slide having an operating projection, guides for the slide, a controller moving with the slide, means whereby the controller is normally held in inoperative position, a magnet for which the controller forms the armature, said magnet operating to retain the controller in its inoperative position when energized, a stop engaged by the controller when the magnet is deenergized, and means for actuating the slide, substantially as described.

30. In a lock, the combination with a bolt having a projection, of a slide having means for engaging with said projection, guides for the slide, a pivoted controller mounted on the slide and normally held in inoperative position by one of the guides, a magnet of which the controller forms the armature, said magnet operating when energized to retain the controller in its inoperative position, means for preventing the controller from touching

the poles of the magnet, a stop engaged by the controller when the magnet is deenergized, a rack for moving the slide, and a hand-operated segment for engaging the rack, substantially as described.

31. In a lock, the combination with one of the engaging parts, said part having a projection, of a slide having means for engaging said projection, said means being normally out of engagement with the projection, whereby the slide is permitted to have a limited movement without operating the engaging part, a controller moving with the slide, a magnet for which the controller forms the armature, the magnet operating when energized to retain the controller in inoperative position, and a stop engaged by the controller when the magnet is deenergized, said stop being located so as to permit a limited movement of the slide before the controller engages its stop, substantially as described.

32. In a lock, the combination with one of the engaging parts, of an operating-slide therefor, a controller moving with the slide, said controller having a cam-face, a stop engaged by the controller, means for holding the controller in a normally-inoperative position, said means and stop being located so as to permit a limited movement of the slide and controller, a magnet for retaining the controller in an inoperative position when energized, and a cam-face on the controller, said cam-face being arranged to engage the holding means for raising the controller as the slide resumes its normal position, substantially as described.

33. In a lock, the combination with a slide and the means for moving it, of a controller moving with the slide, said controller having a cam-face, means with which said cam-face engages for operating the controller, and a stop with which the controller engages, substantially as described.

34. In a lock, the combination with one of the engaging parts, of an actuating device, connections between the actuating device and the engaging part, a magnet for controlling the connections, a suitable circuit therefor, and two sets of circuit-controlling devices, one set of said circuit-controlling devices being operated by the actuating device, substantially as described.

35. In a lock, the combination with one of the engaging parts, of an actuating device, mechanical connections between the actuating device and the engaging part, a magnet for controlling the connections, a suitable circuit therefor, and two sets of circuit-controlling devices, one set of said circuit-controlling devices being operated by the actuating device, substantially as described.

36. In a lock, the combination with a movable engaging part, of means whereby it is moved to open the lock, a magnet, devices operated thereby to control the operation of said moving means, a suitable circuit for the magnet, and two sets of circuit-closing de-

vices, one set of said devices being operated by the means which move the engaging part, substantially as described.

37. In a lock, the combination with one of the engaging parts, of means for moving it, a controlling-magnet located in the lock-easing, a suitable circuit for the magnet, and two sets of circuit-controlling devices, one set of said devices being located within the lock-easing and operated by the moving means, substantially as described.

38. In a lock, the combination with one of the engaging parts, of an actuating device therefor, connections between said device and the engaging part, a controlling-magnet, a suitable circuit for the magnet, and two sets of circuit-controlling devices, one set of said circuit-controlling devices being operated by the actuating device, the arrangement being such that the actuating device operates said set of circuit-controlling devices before it operates the connections, substantially as described.

39. In a lock, the combination with one of the engaging parts, of an actuating device therefor, mechanical connections between said device and the engaging part, a controlling-magnet, a suitable circuit for the magnet, and two sets of circuit-controlling devices, one set of said circuit-controlling devices being operated by the actuating device, the arrangement being such that the actuating device operates said set of circuit-controlling devices before it operates the connections, substantially as described.

40. In a lock, the combination with one of the engaging parts, of operating connections therefor, a controlling-magnet, a suitable circuit for the magnet, two sets of circuit-controlling devices, and a rotating actuating device normally out of engagement with the operating connections, said device also actuating one set of the circuit-controlling devices, said device being arranged to first operate said set of circuit-controlling devices and then the connections, substantially as described.

41. In a lock, the combination with one of the engaging parts, of suitable connections for operating the same, said connections including a rack, a controlling-magnet, a suitable circuit therefor, two sets of circuit-controlling devices therefor, a rotating actuating device having a toothed segment for engaging the rack, said segment being normally out of engagement with the rack, and means whereby the rotating actuating device is caused to operate one set of circuit-controlling devices before its segment comes into engagement with the rack, substantially as described.

42. In a lock, the combination with one of the engaging parts, of a slide for operating it, a controller for the slide, a magnet for determining the position of the controller, a suitable circuit for the magnet, two sets of circuit-controlling devices, a rack for operating the slide, an actuating device including

a rotating toothed segment for operating the rack, said segment and rack being normally disengaged, and means whereby the actuating device operates one set of the circuit-controlling devices before the segment engages the rack, substantially as described.

43. In a lock, the combination with one of the engaging parts, of two actuating devices therefor, connections between one of the actuating devices and said engaging part, connections between the other actuating device and said engaging part, a controller mounted on the last-named connections, and means for operating the controller to cause said connections to open the lock, substantially as described.

44. In a lock, the combination with one of the engaging parts, of two actuating devices, a slide between one of the actuating devices 20 and the engaging part, a slide between the other actuating device and said engaging part, a controller mounted on one of said slides, and means for operating the controller to make the movement of the slide effective 25 to operate the engaging part, substantially as described.

45. In a lock, the combination with one of the engaging parts, of two actuating devices, a slide between one of the actuating devices 30 and the engaging part, a slide between the other actuating device and said engaging part, a controller mounted on one of said slides, and a magnet for operating the controller to make the movement of said slide

effective to operate the engaging part, substantially as described.

46. In a lock, the combination with one of the engaging parts, of two actuating devices, a slide between one of the actuating devices and the engaging part, a slide between the other actuating device and said engaging part, a controller mounted on one of said slides and governing its movement, and a magnet for actuating the controller, substantially as described.

47. In a lock, the combination with a sliding bolt having an operating projection, of two slides provided with means for engaging said projection, an independent actuating device for each of the slides, said actuating devices lying on different sides of the bolt, a controller for one of the slides, the said controller moving with the slide, a magnet located in the path of the controller and operating to determine the position of the controller, a suitable circuit for the magnet, and two sets of circuit-controlling devices for the magnet, one of said sets of circuit-controlling devices being arranged to be operated by one of the actuating devices, substantially as described.

In testimony whereof I have hereunto set my hand in the presence of two subscribing witnesses.

HENRY GUY CARLETON.
